UNITED STATES PATENT OFFICE.

CHARLES T. CROSSMAN, OF ATTLEBORO, MASSACHUSETTS.

DESIGN FOR A RING, EMBLEM, OR ARTICLE OF SIMILAR NATURE.

54,605.

Specification for Design.

Patented Mar. 9, 1920.

Application filed June 13, 1919. Serial No. 304,062. Term of patent 3½ years.

To all whom it may concern:

Be it known that I, CHARLES T. CROSSMAN, a citizen of the United States, residing at the city of Attleboro, county of Bristol, Commonwealth of Massachusetts, have invented a new, original, and ornamental Design for a Ring, Emblem, or Article of Similar Nature, of which the following is a specification, reference being had to the accompanying drawing, forming part thereof.

The figure is a face view of a ring, emblem, or article of similar nature, illustrating my new design.

I claim:

The ornamental design for a ring, emblem, or article of similar nature, as shown.

CHARLES T. CROSSMAN.
